UNITED STATES PATENT OFFICE.

HARRY H. SCHROYER, OF CHICAGO, ILLINOIS, ASSIGNOR TO DUNBAR MANUFACTURING COMPANY, A CORPORATION OF ILLINOIS.

WEATHER-GUARD.

1,335,395.

Specification of Letters Patent. Patented Mar. 30, 1920.

Application filed August 15, 1911. Serial No. 644,256.

To all whom it may concern:

Be it known that I, HARRY H. SCHROYER, a citizen of the United States, and a resident of the city of Chicago, county of Cook, and 5 State of Illinois, have invented certain new and useful Improvements in Weather-Guards, of which the following is a specification.

My invention relates to sliding windows, 10 and has for its object to provide an improved weather guard construction for the same adapted yieldingly to hold the window sash from rattling, and to prevent the passage of dust and moisture between the sash 15 and its frame.

More specifically, the invention embodies 20 the combination of a guard plate on the window frame, a cover plate on the sash overlapping said guard plate, and a resilient 25 means disposed between said sash and guard plate to hold said guard plate and cover plate in close relation, the window sash otherwise fitting loosely in its frame, so as to have some inward and outward play, 30 whereby said resilient means may be free to force the sash inward to accomplish said result.

In the accompanying drawing:—

Figure 1 is a horizontal section taken 35 through the lower sash and the frame of a car window, and illustrates one embodiment of my invention.

Fig. 2 is a view similar to Fig. 1, illustrating a slightly modified construction.

35 Fig. 3 is a fragmentary central vertical section of a car window and frame as shown in Fig. 1.

Fig. 4 is a view similar to Figs. 1 and 2, illustrating another embodiment of my invention.

In the said drawing, the reference numeral 1 denotes the window sill, 2 the inner sill, and 3 the side jambs of a car window, the latter having secured thereon the inner 45 curtain stops 4 and the outer window stops 5, as usual. In the construction illustrated in Figs. 1 and 3, the inner window stop 6 (which is also the outer curtain stop) is secured intermediate said inner and outer 50 stops 4 and 5, to divide the space between said stops into a groove or track X for the curtain fixture, and a similar groove or track for the lower sash. Said stop 6, as shown, is constructed of a metallic sheet or 55 plate bent to provide the stop, rectangular

in cross section, integral with which is a flange 7, which extends outwardly to the outer stop 5, and thence is bent at substantially a right angle to provide a guard plate 8, extending outwardly parallel the outer 60 face of the sash beyond said outer stop 5. Said guard plate is then again bent inwardly to provide a free spring lip or flange 9, which extends to near the flange 7, and bears at all times with considerable pressure 65 against the outer face of the sash. Fixed at one edge to the outer face of the sash is a cover plate 10, the free edge of which extends over the guard plate 8. Said plate 10 is somewhat resilient, and at all times 70 exerts a yielding pressure on said guard plate 8 sufficient to prevent the escape of moisture past the same, and, together with the spring flange 9 of the guard plate 8, affords a double seal against dust and mois- 75 ture.

The construction illustrated in Fig. 2 is identically the same as that before described, except that the side rails of the sash are rabbeted to receive the guard plate 80 8 and flange 9 therein, thereby permitting the cover plate 11, which corresponds with the cover plate 10, before described, to be applied as a flat plate with the same effect as before.

Where a wooden parting strip or stop 12 is used to provide the outer curtain stop and the inner sash stop, a plate of metal is rolled to provide a V-shaped strip, the outer side 13 of which may be concaved or bent 90 inwardly, as shown in Fig. 4, to facilitate fastening the same in place, and the inner resilient flange 14 of which depends laterally and bears against the sash, as before described. The cover plate 10, before described, then is 95 secured on the outer face of the sash to engage over the outer side 13 of said plate to seal the same.

The upper sash 15 is seated ordinarily in the outer stop, as shown in Fig. 3, and is not movable. If the same also is constructed to slide, corresponding weather guards may be provided therefor, if desired.

The operation is as follows:

When applied to car windows it is, of course, understood that the movement of the car tends to cause the sash to hug the inner stop through the inward air pressure thereon. The resilient flange 9, however, insures this position of the sash by pressing the same

inwardly against the stop 6 at all times, the same acting as a spring though its pressure is insufficient to interfere with the sliding of the sash. The cover plate 10 or 11 at its 5 free edge engages over the guard plate 8, and as the sash constantly is forced inward by the action of the resilient flange 9, said cover plate 10 or 11 necessarily is forced thereby into close relation with said guard 10 plate 8 thereby providing a most effective outer seal. And this sealing contact of the cover plate 10 or 11 with the guard plate 8 is aided by the inward pressure of the air upon the window when the car is in motion. 15 The operation of the construction illustrated in Fig. 4 is substantially identical with that before described, the inner stop 12 for the window in this construction being shown as constructed separately and of 20 wood, or of any other suitable material. The same double sealing effect and the resilient bearing of the sealing flange 14 against the window sash assures, however, substantially the same results as before described. 25 While I have shown and described my improved construction as applied to a window, it will be understood that it may be applied equally well to a sliding door construction.

30 I claim as my invention:

1. The combination with a window frame, and a sliding sash fitting loosely therein so as to have inward and outward play, of a guard plate secured to said frame, a cover 35 plate on the sash overlapping said guard plate and unobstructed on its outer surface to permit said inward and outward play of the sash, and resilient means acting between the sash and guard plate to force said 40 sash inward so as to hold said guard plate and cover plate in close relation.

2. The combination with a sliding window

sash, and its frame, of inner and outer window stops on said frame between which said sash is disposed, a guard plate secured 45 to said frame and projecting beyond said outer stop and overlapping the outer face of said sash, a cover plate on said sash engaging the outer face of said guard plate, and resilient means acting between the sash 50 and guard plate and secured to one of the same for holding said sash against its inner stop and for holding said guard and cover plates in close relation.

3. The combination with a sliding window 55 sash, and its frame, of inner and outer window stops on said frame between which said sash is disposed, a guard plate secured to said frame and projecting beyond said outer stop and overlapping the outer face of said 60 sash, said plate being bent inwardly to provide a free spring tongue which bears against the outer face of said sash, and a cover plate secured to said sash and at its free end engaging the outer face of said guard plate. 65

4. The combination with a sliding window sash, and its frame, of inner and outer stops on said frame between which said sash is disposed, a guard plate secured to said frame and projecting beyond said outer stop to 70 overlap the outer face of said sash and again bent inwardly to provide a free spring tongue which bears against said outer face of said sash, and a removable cover plate secured to said sash and at its free end en- 75 gaging the outer face of said guard plate.

In testimony whereof I have hereunto subscribed my name in the presence of two subscribing witnesses.

HARRY H. SCHROYER.
